Reynolds Webb & Jonathan Cox

Sellers Patent

X5854

The Schedule referred to in these Sellers Patent and making part of the same containing, a description in the words of the said Reynolds Webb & Jonathan Cox themselves of their improvement in the common press used for preparing Cheese &c.

To all persons to whom these presents shall come. Be it known that we Reynolds Webb & Jonathan Cox both of Madison, County of New Haven, State of Connecticut, have jointly invented a new & useful improvement in the common press used for preparing Cheese & for other similar purposes, which improvement or invention we specify and describe as manner following (viz.)

To show the nature, properties & effects of our improvement we have describe a portable press of a size suitable for preparing the cheese made from an ordinary dairy & so constructed as to admit of a convenient application of the principle of our invention. The drawing annexed exhibits a perspective view of the machine here described & references are made to the same in this description. In the construction of the machine some kind of hard wood, such as oak or maple which will work neatly & fit accurately, should be used. The foot-panes or sills (a. a.) are two feet long, two inches wide & two inches thick. To these foot-panes are firmly fastened two upright or perpendicular pieces (b. b.) two feet four inches long, three & a half inches wide & two inches thick. To these upright pieces by inches distance from the foot-panes is fitted or framed a soft piece (c.) one foot & ten inches long, seven inches wide & one inch thick, to form a base to support the substance to be pressed. This joint the upright pieces in a direction perpendicular to the foot-panes upon the base or board (c.) is placed a sufficient number of soft pads to be inter-

is to be provided with a channel (e.) and will be circular or oval
form & leading off from one edge of the frame in order to release
any liquid matter which may be discharged. A second cross
piece (f.) parallel to the first, one foot & ten inches ^{long} three inches
wide & two inches thick, is fitted with a notch at each end
of the width of the perpendicular pieces so as to slide freely up &
down as the pressure is applied or removed. At each end of
this last piece are placed two upright or perpendicular pieces
(g. g.) (g. g.) the two pieces which form each pair are
three fourths of an inch distant from each other. The two
outer pieces of each pair (g. g.) are four & a half inches long & three
& a half inches wide & three fourths of an inch thick & rounded
at top. The two inner pieces (g. g.) are one foot three inches
long. Three & a half inches wide & one inch thick, & in the top
per part of these inner pieces are two mortises or openings (h. h.)
eight and a half inches long, & two inches wide rounded at each
end of the openings & the whole pieces rounded at the top.
Between each of these pairs of upright pieces & one & a half
inch distance from the ends of the shorter pieces is placed a small
wheel (i. i.) two inches in diameter & three fourths of an inch
thick with pins running thru the pairs of upright pieces &
thru the centre of each wheel half an inch in diameter, the
two wheels & pins are formed of iron, brass, or other hard metal.
There is a third cross piece (k.) circular in its shape but
largest in the middle. the circumference at the ends is six
inches & in the middle eight inches with three or more holes
near the middle one inch in diameter intended to receive a
lever. This cross piece is one foot six inches long & on each
end of it is placed a metal gudgeon (l.) four inches in length
which may run in a metal key placed on the upper part of each
upright piece (l. h.) three inches from the top of the same. The
gudgeon & key should be iron or brass & well hardened.
The two ends of the middle cross piece are provided for

the distance of one inch & a quarter from each end, each side of the square is one inch & a half. Upon these square parts are fitted two curved or spiral, or scroll pieces made of iron or other hard metal (m. m.) five eighths of an inch in thickness with open ends & braced so as to secure both lightness & strength, but where these are not regarded they can be solid & these are to be so fitted as to run upon the wheels (i. e.) with accuracy, when the circular crop piece (k.) is turned round by means of the lever (n.) of suitable length & size & fitted to enter the holes in the same. This lever also may have two or three or more notches or grooves cut round the same so that when a constant pressure is needed a weight may be hung upon the lever when in an elevated position) & not slide down towards the circular crop piece. The weight to be applied may be a stone, bag of sand, or other suitable heavy matter. When a constant pressure is not needed, any other common power may be applied. By varying the size & proportion of the parts fitted may be made larger or smaller according to the size to which they are to be applied, also the curved spiral or scroll pieces (m. m.) of shapes as represented in the annexed drawing, will by means of the proportions (c. o.) fitting to the wheels (i. e.) when the crop piece (f.) is raised as high as it can be held without pulling the crop piece (f.) from descending, by its own weight, which may be some convenience in using the fence. The curved spiral or scroll pieces may be formed with the outer edge or periphery decreasing more or less rapidly from the central point, but on experience leads us to the conclusion that a curve or spiral which at the point on the circumference, where it is first made to operate is one inch & a half distant, measured on a radius or ordinate from the center of its motion so as to give it suitable lightness & strength at the distance of one inch measured from the first mentioned point upon the periphery, has wings

three inches from the centre of motion measured on a radius or ordinate, and again on the distance of twenty inches, measured from the first mentioned point & measured on the periphery or outer curve, is five inches & one quarter distant from the centre of motion measured on a radius or ordinate, is best adapted to the press of the size we have described & in the same ratio of proportion for larger or smaller presses. Fig 3 Exhibits a spiral detached from the machine. To use the press the cross piece (f) is raised by blocking on the substance to be pressed, till the small wheels (i, i, i,) come in contact with the spiral pieces (m, m, m,) & if you wish to move the cross piece (f,) thro' all the distance which it can be carried by the spirals (m, m, m,) you bring the wheels (i, i, i,) and the spirals (m, m, m,) in contact as near to the central points of the spirals (m, m, m,) as possible, then introduce the lever (n) into the holes in the circular cross piece (h,) & the weight or other power is applied to the lever (n,) causing the cross piece (h,) to revolve & carry with it the spirals (m, m, m,) which press upon the wheels (i, i, i,) which also revolve & the spirals (m, m, m,) press down the cross piece (f,) with great force upon the substance placed under it & intended to be pressed, while the cross piece (f,) by means of the mortises (h, h,) in the upright pieces (g, g,) is kept parallel to the base (c,) & side board (a,) & each side of the substance pressed is kept by of the same thickness or width. This press is simple in its construction easily managed & kept in order, portable & requires great power, which is easily brought into operation & very little retarded or diminished by friction. While perhaps slight variations in construction presses may be formed upon this plan, with some improvements adapted to advantage, for purpose for which presses are used. What we claim as our invention or improvement is the combination of the base of the board and wedge in one line plan by means of a circular cross piece & the cross piece so small, being only one third the size of the base.

X5854

thrust & operating on the two small wheels as described & set forth in the foregoing specification, whereby great power to press is obtained & that power made to operate in a convenient, cheap & uniform manner & with but a small loss of power by friction. But we do not claim as any part of our invention the whole or any of the parts of the above described press, now or formerly in use in the particular size or shape of the same any farther than is necessary to combine the above powers & bring them to operate in combination & remove or lessen friction during their operation.
